A. L. DAY.
PERFORATING MACHINE.
FILED JUNE 1, 1920.

Inventor
Alfred L. Day

by Heard Smith & Thorne
Atty.

UNITED STATES PATENT OFFICE.

ALFRED L. DAY, OF BROOKLINE, MASSACHUSETTS, ASSIGNOR TO DAY PERFORATOR COMPANY, A VOLUNTARY ASSOCIATION OF MASSACHUSETTS.

PERFORATING MACHINE.

Application filed June 1, 1920. Serial No. 385,466.

To all whom it may concern:

Be it known that I, ALFRED L. DAY, a citizen of the United States, residing at Brookline, county of Norfolk, State of Massachusetts, have invented an Improvement in Perforating Machines, of which the following description, in connection with the accompanying drawing, is a specification, like characters on the drawing representing like parts.

This invention relates to perforating machines and has for its principal object to provide a novel perforating machine which is constructed so that at each actuation thereof it will deliver a slip of paper which has been perforated. A machine embodying the invention is provided with a magazine containing a plurality of slips of paper to be perforated and means for ejecting and delivering from the machine each slip as it is perforated. The invention is capable of various uses such, for instance, as making perforated records of different sales in a store, or perforated records of goods delivered, in which case the perforating mechanism will preferably be adjustable so that it can be set at each actuation to perforate the numbers or characters desired.

The invention has the advantage that it obviates the necessity of introducing a slip or sheet of paper into the machine to receive the perforated record because the slips or sheets on which the perforated records are to be made are contained within the machine and are delivered automatically as the machine is actuated.

In order to give an understanding of my invention, I have illustrated in the drawings a selected embodiment thereof which will now be described, after which the novel features will be pointed out in the appended claims.

In the drawings, Fig. 1 is a side view of a perforating machine embodying my invention with a portion broken out to better show the interior construction;

Fig. 2 is a front view of Fig. 1;

Fig. 3 is a detail view of the trip mechanism for controlling the shears;

Fig. 4 is a plan view of the mechanism shown in Fig. 3;

Fig. 5 is a section on the line 5—5, Fig. 4.

The device herein shown comprises a base frame 1 having a throat 2 through which the slips of paper are ejected and also having a

die-plate 3 situated beneath the throat and provided with apertures to receive punches 4 which are situated above the throat and are properly guided in their vertical movement. The punches are arranged in groups, and means are provided for selectively actuating the punches of each group thereby to perforate any desired character in a slip or sheet of paper which may be supported on the die-plate 3. This selective actuation of the punches is accomplished by a matrix member, as usual in perforating machines of this type. If the machine is designed to perforate a plurality of characters simultaneously, then it will be provided with a plurality of groups of punches 4 and a corresponding number of matrix members. In the machine shown in the drawing, there are four such groups of punches, and four matrix members, the latter being indicated at 5 and being pivotally mounted on a shaft 6 carried in a moving head 7. This head is shown as having a rearward extension 8 which is pivoted to the base frame at 9. Each matrix member 5 has the circular face 10 in which is formed a plurality of groups of recesses, the recesses of each group being so arranged relative to each other that the solid portions between the recesses represent some particular character. Each matrix member 5 is adjustable on the shaft 6 to bring any group of recesses into line with the group of punches, and when the matrix member has been thus properly adjusted or set, downward movement of the head will bring the matrix member against the punches, and those punches which stand opposite recesses will not be depressed, but will remain in their elevated position while the punches which are opposite solid portions of the matrix will be depressed and forced through the die-plate 3 thereby perforating any slip or sheet of paper which may be resting on the die-plate.

The matrices may be adjusted in any suitable way. Each is herein shown as having a circular extension 11 provided with a thumb-piece 12 which extends through a slot 13 in the head and by which the matrix may be turned about the shaft to bring any group of recesses into line with the punches.

The parts thus far described are or may be all as illustrated and described in my co-pending application Ser. No. 379,162, filed May 5, 1920.

In the present embodiment of the inven-

tion the head 7 is given its movement by means of an eccentric 14 fast on a shaft 15 which is journaled in the base frame 1 and extends transversely thereof. This eccentric 5 is provided with an eccentric strap 16 having an arm 17 which is pivoted to the head at 18. With this construction, each rotation of the shaft 15 will lower the head thereby actuating the punches and then raise the head again. 10

Associated with the base frame 1 is a magazine containing a plurality of slips or sheets of paper to be perforated, and means are provided whereby upon each actuation of the 15 machine one slip will be perforated and then will be delivered from the machine.

The magazine may be made in various ways without departing from the invention. Perhaps the most convenient form of magazine is that herein shown which is in the 20 nature of a roll of paper which is situated within the base frame 1 and is constructed so that at each actuation of the machine a length of paper will be withdrawn from the roll and severed and delivered from the machine. 19 indicates a roll of paper which is rotatably mounted on a shaft 20 carried by the base frame. The strip of paper 31 from the roll extends through the throat 2 and over the die-plate 3, and means are provided whereby each time that the punches are actuated to perforate the portion of the strip of paper 31 which is over the die-plate 3, the portion of the strip which is thus perforated 25 will be delivered from the throat 2 and will then be severed from the strip thereby leaving an unperforated portion of the strip beneath the punches for the next actuation of the machine.

40 The feeding of the strip of paper from the roll 19 may be provided for in various ways without departing from the invention. One convenient feeding device is that shown which comprises the two feed rolls 21 and 22 45 rotatably mounted upon the shafts or pins 23 and 24. These rolls may conveniently be rubber-covered or have some friction surface so that they will have sufficient frictional engagement with the strip of paper to ensure that it is properly fed as the rolls are rotated. I have provided herein means for 50 rotating the rolls intermittently, the rotary movement occurring just after the punches have been depressed and have been elevated sufficiently to clear the perforated paper. Various means for rotating the rolls may be 55 provided, and as illustrating one simple construction, I have shown a segmental gear 25 fast on the shaft 15 and adapted to engage a pinion 26 integral with the feed roll 21. The gear 25 is so shaped and disposed that it will 60 only mesh with the gear 26 while the head is being carried through the last part of its upward movement. The parts are shown in Fig. 1 in the position they would assume 65

when the machine is at rest. The operation of the machine involves turning the shaft 15 through one complete revolution in a clockwise direction, and this may conveniently be done by means of a handle or crank 27 70 which is fast on the shaft. During the first half of the revolution of the shaft, the head 7 will be depressed thereby performing the perforating operation, and during the last half of the revolution the head 7 will be elevated. 75 When the head is elevated about half-way or has been raised sufficiently to clear the punches from the paper, then the gear 25 comes into mesh with the gear 26, and during the final upward movement of 80 the head, the roll 21 is rotated thereby feeding the paper forward, and by the time the head is completely raised and the shaft is brought to rest in the position shown in Fig. 1, the gear 25 will be just clear from the gear 26. The size of the gears and the size of the rolls are so proportioned as to feed the paper the proper amount before the gear 25 is carried out of mesh with the gear 26. 85

If desired, the rolls 21 and 22 may be 90 geared together so that both will be positively rotated.

It is sometimes desirable to have a duplicate copy of each perforated record made, and when this is the case, I propose to employ a second roll 28 which is mounted on the shaft 29 and which delivers a strip of paper 30 through the throat in addition to the strip 31. Both strips of paper may pass 95 between the feed rolls 21, 22 and thus be fed 100 simultaneously.

My invention also contemplates means for automatically severing from the strips 30 and 31 the portion thereof which has been perforated after the perforation has been 105 made, thereby providing the separate perforated slip. This severing of the slips from the strip is accomplished by means of a shear device situated at the delivery end of the throat 2 and which is actuated just after the 110 paper has been fed forward sufficiently to eject the perforated portion of the strips from the throat. This shear device comprises a fixed shear blade 32 situated above the throat, and a movable shear blade 33 115 which is pivoted to the base at 34. The blade 33 extends beyond the pivot, as shown at 35, and is acted upon by a spring 36 which tends to swing it into closed relation with the fixed shear blade 32. 120

Means are provided for automatically opening the shears by swinging the blade 33 downwardly into the dotted line position while the paper is being fed and then releasing the blade to allow the spring 36 to 125 actuate it to shear off the length. For thus opening the blade, I provide a latch 37 which is pivoted to a lug 38 extending from the side of the head 7 and which operates in a slot 39 formed in the side wall of the base 1. 130

This latch 37 is acted upon by a spring 40 which tends to swing it outwardly. The lower end of the latch is beveled, as shown at 41, and the end of the blade 33 is provided 5 with a pin 42. When the head moves downwardly, the beveled portion 41 of the latch 37 engages the pin and swings the latch backwardly, and by the time the head has completed its downward movement, the 10 latch is carried below the pin and is swung outwardly beneath the pin by the spring 40. As the head rises, the latch by its engagement with the pin 42 will swing the blade into the dotted line position, Fig. 2, thereby 15 placing the spring 36 under increased tension, and carrying the blade below the mouth of the throat so that the strips of paper may be fed forward and delivered therefrom.

20 Means are provided for releasing the latch from the pin just at the time when the head completes its upward movement thereby permitting the spring 36 to act to close the shears and cut off the perforated lengths from 25 the strips 30 and 31. This is herein accomplished by means of a lever 43 pivoted to the frame at 44, and one end of which is adapted to engage the latch 37. The other end of 30 the lever is adapted to be engaged by a beveled arm 45 carried by the shaft 15, and this arm is so positioned that it will engage the lever 43 just as the shaft 15 completes its rotation. The engagement of this arm 45 with the lever 43 will swing the lever 35 about its pivot thereby forcing the outer end of the lever inwardly toward the frame and forcing the latch 37 backwardly out of engagement with the pin 42. The engagement of the arm 45 with the lever 43 serves not 40 only to release the latch 37, but also to give the operator indication as to the proper point at which to stop rotation of the shaft 15.

The slips which are severed fall onto the 45 platform portion 46 of the frame from which they may be removed by the operator.

I may if desired provide a strip of paper 47 which is wound on reels 48 and 49 and 50 on which a record of all perforations may be made. The portion of the strip of paper between the rolls 48, 49 passes over the die-plate 3 beneath the strips 30 and 31, and,

therefore, whenever the machine is operated, a perforated record will be made in 55 the strip 47. This strip 47 is fed intermittently so that the successive perforations will be made at different places along the strip. This feeding of the strip 47 is accomplished by gearing the roll 49 to the roll 31 60 by means of an intermediate gear 50 which meshes with the gear 26 and also with the gear 51 on the roll 49. Hence at each feeding movement of the strips 30 and 31, the strip 47 will be fed forward. 65

I claim:

1. In a perforating machine, the combination with perforating mechanism comprising a die plate, a plurality of punches, a vertically-swinging head carrying matrices to 70 selectively operate the punches, of a shaft having an eccentric thereon connected to said head for actuating the latter, and means actuated by the rotation of said shaft to feed sheet material into position to be 75 perforated.

2. In a perforating machine such as described in claim 1, means actuated by the shaft during a portion only of each rotation thereof to feed the sheet material. 80

3. In a perforating machine, the combination with perforating mechanism comprising a die plate, a plurality of punches, a vertically-swinging head carrying matrices to 85 selectively operate the punches, of an actuating shaft, means to move the head downwardly to produce a perforating operation and then to raise the head again at each rotation of the shaft, and means operative during the last portion of each rotation of the 90 shaft to feed sheet material into position to be punched.

4. In a perforating machine, the combination with perforating mechanism, of means to actuate it, means to feed a strip of paper 95 so as to bring different portions of it successively into position to be perforated, a knife for severing the perforated portions of the strip, means actuated by the actuating mechanism for the perforating mechanism 100 to swing on said knife in one direction, and a spring to give the knife its cutting movement.

In testimony whereof, I have signed my name to this specification.

ALFRED L. DAY.
